Primary Examiner—Benjamin H. Layno(74) *Attorney, Agent, or Firm*—Bell, Boyd & Lloyd LLC(57) **ABSTRACT**

The player makes a wager for each separate hand to be played. One hand of four cards are dealt. The player selects cards from the first hand as cards to be held which are reused from the first hand into all of the other hands. Replacement cards for the non-selected cards are dealt into the first hand and an additional card is dealt so that the first hand has five cards. Additional cards are also dealt to all of the other hands so that each hand is a five card hand. The poker hand ranking of each hand is determined. The player is then paid for any winning poker hands based on a pay table and the amount of the player's wager.

The disclosure of each of these earlier applications is incorporated herein by this reference, with each of these earlier applications being commonly owned with this application.

BACKGROUND OF THE INVENTION

This invention relates primarily to electronic video poker games, and more particularly to electronic video poker games that are based on poker hand rankings and that allow the player to discard and replace unwanted cards with replacement cards. The present invention has many versions with the common thread being that cards are duplicated from an initial hand of cards into one or more additional hands to allow the player the opportunity to play one or more cards from the starting hand of cards multiple times. The invention also involves features which may apply to casino table games as well.

SUMMARY OF THE INVENTION

The method of the present invention involves a card game in which the player plays multiple hands of cards. The player makes a wager for each row of cards and each row of cards becomes a separate hand to be played by the player. One hand of two, three, four or five cards are dealt all face up. The player selects none, one or more of the face up cards from the first hand as cards to be held. The cards that are held are duplicated from the first hand into all of the other hands. Replacement cards for the non-selected cards are dealt into the first hand and additional cards are then dealt to the first hand, if needed, so that the first hand has five cards. Additional cards are also dealt to all of the other hands so that each hand is a five card hand. The poker hand ranking of each five card hand is determined row by row. The player is then paid for any winning poker hands based on a pay table and the amount of the player's wager.

Alternatively, the method of the present invention can also be applied to three card poker or four card poker.

BRIEF DESCRIPTION OF THE DRAWINGS

FIG. 1 shows the screen display for Version #A of the present invention after the initial deal of the cards.

FIG. 2 shows the screen display for Version #A after the player has selected the cards he wishes to hold from the center row.

2

FIG. 3 shows the screen display for Version #B of the present invention after the initial deal of the cards.

FIG. 4 shows the screen display for Version #B after the player has selected the cards he wishes to hold from the top row and a replacement card has been dealt to the top row.

FIG. 5 shows the screen display for Version #B after all three row have been completed and show five card hands.

FIG. 6 shows the screen display for a variation of Version #B which uses five rows of cards after the initial deal of the cards.

FIG. 7 shows the screen display for another variation of Version #B which uses ten rows of cards after the initial deal of the cards.

FIG. 8 shows the screen display for still another variation of Version #B which uses ten rows of cards after the initial deal of cards in which all of the rows have the same cards displayed face up.

FIG. 9 shows the screen display for Version #C of the present invention after the initial deal of the cards.

FIG. 10 shows the screen display for Version #D of the present invention after the initial deal of the cards.

FIG. 11 shows the screen display for Version #D after the player has selected the cards he wishes to hold from first hand and these cards have been duplicated into the other two hands.

FIG. 12 shows the screen display for Version #D after all three rows have been completed and show five card hands.

FIG. 13 shows the screen display for the three card poker Version #E of the present invention after the initial deal of the cards.

FIG. 14 shows the screen display for the three card poker Version #E after the player has selected the cards he wishes to hold from first hand and these cards have been duplicated into the other two hands.

FIG. 15 shows the screen display for the three card poker Version #E after all three rows have been completed and show five card hands.

FIG. 16 shows the screen display for the four card poker Version #E of the present invention after the initial deal of the cards.

FIG. 17 shows the screen display for the four card poker Version #E after the player has selected the cards he wishes to hold from first hand and these cards have been duplicated into the other two hands.

FIG. 18 shows the screen display for the four card poker Version #E after all three rows have been completed and show five card hands.

DETAILED DESCRIPTION OF THE PREFERRED EMBODIMENTS

The present invention includes a variety of electronic video poker games each having multiple hands in which the player selects zero, one or more cards from a first hand and the selected cards are duplicated into each of the other hands. Each of the hands receives additional cards so that each hand is a complete poker hand. Each electronic video poker game is designed to be played by having the hands displayed on a video screen to a player. By manipulating the buttons on the button panel of the gaming device or by using conventional touch screen technology, the player selects which cards he wishes to play, which cards he wishes to duplicate into other hands and which cards he wishes to discard. The player activates a draw button and replacement cards are then displayed for the discarded cards. The result-

ing competed hands are analyzed for poker hand ranking and the outcome of the play of each hand is determined. The player wins awards based on the poker hand rankings of the completed hands and the amount wagered by the player on each hand using a pay table that is displayed to the player.

Version #A: FIG. 1 shows the layout for the initial deal of one version of the present invention. Three rows of cards are initially dealt. The center row **310** is dealt face up; the bottom row **320** and the top row **330** are dealt face down. Also, a face down card **311A**, **312A**, **313A**, **314A** and **315A** is dealt underneath each of the respective face up cards **311**, **312**, **313**, **314** and **315** in the center row **310**.

The player makes one, two or three wagers: the first wager is on row **310**, the second wager is on row **320** and the third wager is on row **330**. Thus, the player is playing one, two or three hands at a time.

The player selects those cards in the center row **310** that he wishes to hold. The player effects this selection by pressing buttons or, using touch screen technology, by simply pressing the cards on the screen that the player wishes to hold. Each card that is held by the player from the center row **310** is duplicated in the corresponding vertically aligned position in both the bottom row **320** and the top row **330**. Therefore, three copies of the held card are now displayed on the screen. The player may hold from zero to five cards from the center row **310**.

FIG. 2 shows an example of the play of the hand when the player has held card **311**, card **312** and card **313** from the center row **310**. Card **311**, the Ace of Spades, is duplicated in the same aligned position in top row **330** and in bottom row **320**. Likewise, card **312**, the Jack of Spades, and card **313**, the Ten of Spades, are both duplicated in the same aligned positions in top row **330** and bottom row **320**.

After the player is satisfied with his selection of replacement cards, the player presses the “deal” button and the two face down cards **324** and **325** in bottom row **320** are revealed. Similarly, the two face down cards **334** and **335** in top row **330** are revealed. The two unheld cards **314** and **315** in the center row **310** are replaced with the face down cards underneath them, cards **314A** and **315A**, and these two cards **314A** and **315A** are also revealed.

Each row is treated as a separate hand for payout purposes. Each row is evaluated for poker hand ranking and the player is paid based on the amount of his wager on each row depending on the poker hand ranking achieved for that row.

Thus, the player has effectively played three hands at once. The player could win on all three hands, could lose on all three hands, could win on two hands and lose on one hand or could lose on two hands and win on one hand.

In one of the preferred embodiments of this invention, the method of play uses a separate decks of cards for each hand (or row) of cards that the player wishes to play. For example, in a game in which the player is playing three hands or rows—the first hand is dealt using a first standard fifty-two card deck while the second hand is dealt using a second deck of forty-seven cards which comprises a standard fifty-two card deck having the player’s five initial face up cards shown in the first hand omitted therefrom and the third hand is dealt using a third deck of forty-seven cards which comprises a standard fifty-two card deck having the player’s five initial face up cards shown in the first hand omitted therefrom. This would allow the player, for example, to theoretically make three Royal Flushes at the same time in each of the three separate hands. This is accomplished using the computer controls that operate the gaming machine with the software being written so that the second and third decks used to deal

the second and third hands, respectively, have removed therefrom the five cards initially dealt.

In each of the preferred embodiments of the present invention, a standard fifty-two card deck of playing cards is used for each deck. One or more cards may also be designated as wild cards and, alternatively, one or more Jokers may be added to the deck of cards and the Jokers are used as wild cards.

In each of the preferred embodiments of the present invention, the amount of the player’s wager on each hand would be the same. Alternatively, the player could be allowed to make wagers of different amounts on each hand.

Version #B: This version is played similarly to Version #A in that the player can play three hands at once, except for a modification to the manner in which the cards are dealt to the display screen. FIG. 3 shows the layout for the initial deal of this version. Three rows of cards are initially dealt representing the player’s three hands. The top row **410** is dealt face up; the center row **420** and the bottom row **430** are dealt face down. Alternatively, any one of the three rows can be the face up cards with the other two rows being the face down cards.

In one embodiment of the present invention, the player has the option to make one, two or three wagers: the first wager is on row **410**, the second wager is on row **420** and the third wager is on row **430**. Thus, the player is playing one, two or three hands at a time. Alternatively, it could be mandatory that the player must wager on all three hands.

As shown in FIG. 3, the cards dealt to the top row **410** are the Four of Diamonds **411**, the Six of Spades **412**, the Six of Hearts **413**, the Queen of Spades **414** and the Queen of Clubs **415**.

The player selects those cards in the top row **410** that he wishes to hold. The player effects this selection by pressing buttons or, using touch screen technology, by simply pressing the cards on the screen that the player wishes to hold. Each card that is held by the player from the top row **410** is duplicated in the corresponding vertically aligned position in both the center row **420** and the bottom row **430**. Therefore, three copies of each of the held cards are now displayed on the screen. The player may hold from zero to five cards from the top row **410**.

FIG. 4 shows an example of the play of the hand when the player has held card **412**, card **413**, card **414** and card **415** from the top row **410**. Card **412**, the Six of Spades, is duplicated in the same aligned position in center row **420** and in bottom row **430**. Likewise, card **413**, the Six of Hearts; card **414**, the Queen of Spades; and card **415**, the Queen of Clubs are also duplicated in the same aligned positions in center row **420** and bottom row **430**.

After the player is satisfied with his selection of the held cards for each of the three hands, the player presses the “draw” button, the cards to be discarded are removed from the screen display and replacement cards are dealt for the discarded cards to complete each of the three hands. With regard to the hand in the top row **410**, a replacement card is dealt for card **411** which was discarded by the player. As shown in FIG. 5, the new card is the Jack of Clubs **416** which does not improve the player’s hand in the top row **410** which has a final hand ranking of Two Pair.

With regard to the hand in the center row **420**, the last card **421** added to this hand is the Six of Diamonds giving the hand in the center row **420** a final hand ranking of a Full House. With regard to the hand in the bottom row **430**, the last card **431** added to this hand is the Ace of Spades giving the hand in the bottom row a final hand ranking of Two Pair.

5

Each row is treated as a separate hand for payout purposes. Each row is evaluated for poker hand ranking and the player is paid based on the amount of his wager on each row depending on the poker hand ranking achieved for that row. A suitable pay table is provided as is conventional for electronic video poker games with the amount of the player's winnings being based on the poker hand ranking achieved and the amount wagered by the player on each hand.

Thus, the player has effectively played three hands at once. The player could win on all three hands, could lose on all three hands, could win on two hands and lose on one hand or could lose on two hands and win on one hand.

Another alternative to Version #B would be to reduce the three rows shown to only two rows and otherwise practice the method of this version as described. The player would make two wagers to play the two rows and select the cards initially dealt that would be used in each of the two rows. Replacement cards would be provided to complete the hands in each of the two rows and winning and losing hands would be determined in the same manner as described above with reference to the three rows.

Likewise, the method of play described in Version #B could also be modified by increasing the number of rows to four or more, with five rows being the preferred number of rows for this alternative embodiment. Again if four or more rows are used, the method of play would be the same as that described above with reference to the three rows version. In order to show four or more rows of cards at the same time on a video screen display, a larger video monitor may be required.

For example, FIG. 6 shows a screen display with five rows. The player makes appropriate wagers on one or more rows. The lowermost row is displayed first with all five cards face up. The player selects which cards he wishes to hold from the lowermost row and these cards are duplicated into all of the other rows on which the player has wagered. Replacement cards are dealt for the unselected cards in the lowermost row and additional cards are provided to complete each five card hand in the other rows.

However, the preferred embodiment of this version uses five separate decks of cards—the first row being dealt using a first standard fifty-two card deck while the second, third, fourth and fifth rows are dealt using separate decks of forty-seven cards which comprises a standard fifty-two card deck having the player's five initial face up cards shown in the first row omitted therefrom. This would allow the player, for example, to theoretically make five Royal Flushes (or any other five card hands of the same rank) at the same time.

FIG. 7 shows another initial row display in which ten rows of cards are displayed to the player. The player makes appropriate wagers on one or more rows up to a total of ten rows to play all ten rows. Again, the lowermost row is displayed first with all five cards face up. The player selects which cards he wishes to hold from the lowermost row and these cards are duplicated into all of the other rows on which the player has wagered. Replacement cards are dealt for the unselected cards in the lowermost row and additional cards are provided to complete each five card hand in the other rows. In one embodiment of this ten row version, a single deck of cards can be used for all of the rows.

However, the preferred embodiment of this version uses ten separate decks of cards—the first row being dealt using a first standard fifty-two card deck while the second through tenth rows are dealt using separate decks of forty-seven cards which comprises a standard fifty-two card deck having

6

the player's five initial face up cards shown in the first row omitted therefrom. This would allow the player, for example, to theoretically make ten Royal Flushes (or any other five card hands of the same rank) at the same time.

FIG. 8 shows a different way of displaying the ten rows. When the initial lowermost row is dealt, all five of the face up cards from this initial row are also displayed in the other nine rows. The player selects which cards he wishes to hold from the lowermost row and these cards are automatically held in all of the other rows on which the player has wagered. Replacement cards are dealt for the unselected cards in the lowermost row and all of the other rows. The game otherwise proceeds as described in connection with FIG. 18. Either a single deck of cards or ten separate decks of cards are used. This modified method of displaying the cards dealt in each row can also be applied to the other embodiments of the present invention.

In order to adopt any of the various embodiments of the present invention to the smaller video monitors often used in video poker gaming machines, the display of the play of the method of play can be modified. This modified display method can be a seriatim method in which the player plays a plurality of hands one after another. In this seriatim method, the player would initially make a multiple coin, token or credit wager representing the number of hands that the player wishes to play during that round of the game. The minimum number of coins or credits wagered would be two representing two hands that the player wishes to play with the maximum being any number desired. The player can also wager multiple coins per each hand.

After the player has decided on the number of hands and the number of coins to be wagered on each hand, the first hand of five cards would initially be dealt to the player. The player would select which of the initial five cards, if any, the player wishes to hold and then replacement cards would be dealt for the discarded cards. The winning or losing outcome of this first hand would then be determined. The results of this first hand can be displayed in a portion such as the corner of the video display screen as a smaller hand display similar in size to the smaller hands shown in FIG. 8.

For the second hand, the cards held by the player from the first hand would then be redisplayed on the video screen and additional cards would be dealt to complete the player's second hand. Again, the winning or losing outcome of this second hand would be determined. The steps of redisplaying the held cards from the first hand and the dealing of cards to complete the hand would be repeated for each wager made by the player until the total number of hands originally wagered by the player is completed. After each hand is played, the results of each hand can be displayed in a portion such as the corner of the video display screen as a smaller hand display similar in size to the smaller hands shown in FIG. 8. This seriatim method of play can be applied whenever two or more rows are desired to be played.

In this seriatim alternative method of play, each hand is completed by using a separate deck of cards (which have the first five cards removed therefrom so as to eliminate the possibility of duplicated cards being dealt as replacement cards) or by reshuffling the remaining forty-seven cards before each new row is played. Alternatively, a single deck of cards can be used as the source for both the initial five cards and the additional cards used to complete each of the multiple hands.

Version #C: Another alternative method of play of the present invention would have two or more rows of five or more cards all dealt face up with each row having the same

cards shown face up. In the preferred embodiment of this version #C, three rows are displayed face up with each row having the same five cards shown in each hand. As shown in the example in FIG. 9, row 510 is dealt with five cards—the Four of Diamonds 511, the Six of Spades 512, the Six of Hearts 513, the Queen of Spades 514 and the Queen of Clubs 515; row 520 is dealt with five cards—the Four of Diamonds 521, the Six of Spades 522, the Six of Hearts 523, the Queen of Spades 524 and the Queen of Clubs 525; and row 530 is dealt with five cards—the Four of Diamonds 531, the Six of Spades 532, the Six of Hearts 533, the Queen of Spades 534 and the Queen of Clubs 535. The player can then select which cards to hold from any one of the rows and these cards selected by the player are automatically held in the other two rows. Again with reference to the example shown in FIG. 9, the player would most likely hold the Six of Spades, the Six of Hearts, the Queen of Spades and the Queen of Clubs. Whichever cards are selected by the player will automatically be held in each of the rows.

Each row then receives replacement cards for the cards that are discarded, preferably from separate decks for each row. The player has three final five card hands and wins or loses on each hand separately based on a pay table which shows the winning hand combinations. If the player has a winning hand, the amount won by the player is based on the amount wagered by the player on that particular row and the poker hand ranking of the cards in that row. This Version #C may also be applied to methods of play that use only two rows or that use four or more rows.

Version #D: Another alternative method of play of the present invention would have two or more rows of less than a complete five card hand be dealt face up. Then after the player has selected the cards to be duplicated from the first row into the other rows, each row is completed to have five cards. In the preferred embodiment of this version #D, the player wagers on the number of hands the player wishes to play, for example the three rows shown in FIG. 10. The first hand 610 is dealt with one, two, three or four of the cards dealt face up and the remaining cards face down, such as the four face up cards and the one face down card shown in the example in FIG. 10. Hand 610 is dealt with five cards—the Ace of Hearts 611, the Ace of Spades 612, the King of Clubs 613, the Six of Spades 614 and the face down card 615. The player can then select which cards to hold from the first row 610 and these cards selected by the player are automatically duplicated in the other two rows 620 and 630. Again with reference to the example shown in FIG. 11, the player would most likely hold the Ace of Hearts 611 and the Ace of Clubs 612 as the cards to be duplicated into the other hands.

The first hand 610 then receives replacement cards for the cards that are discarded and the face down card 615 is turned face up. In this example as shown in FIG. 12, the first hand has a final hand of the Ace of Hearts 611, the Ace of Clubs 612, the Four of Diamonds 616, the Four of Spades 617 and the Four of Hearts 615. The second hand and the third hand have their face down cards turned face up. The second hand 620 has a final hand of the Ace of Hearts 611, the Ace of Clubs 612, the Ace of Spades 623, the Seven of Diamonds 624 and the Eight of Hearts 625. The third hand 630 has a final hand of the Ace of Hearts 611, the Ace of Clubs 612, the Ace of Diamonds 633, the Four of Hearts 634 and the Ace of Spades 635.

The player now has three final five card hands and wins or loses on each hand separately based on a pay table which shows the winning hand combinations. If the player has a winning hand, the amount won by the player is based on the

amount wagered by the player on that particular row and the poker hand ranking of the cards in that row. For example, again with reference to FIG. 12, in hand 610 the player has a Full House, in hand 620 the player has a Three-of-a-Kind and in hand 630 the player has a Four-of-a-Kind which would all most likely be winning hands based on the pay table.

This Version #D may also be applied to methods of play that use only two rows or that use four or more rows.

Version #E: In another version of the present invention, the method of play can be applied to poker-type games that use less than a five card hand. For example, three card poker and four card poker can be adapted to the present invention.

FIG. 13 shows an initial deal of a three card poker game which allows the player to play multiple hands. In the preferred embodiment of this version #E, the player wagers on the number of hands the player wishes to play, for example the three rows shown in FIG. 13. The first hand 710 is dealt with all three cards face up. Hand 710 is dealt with the Ace of Hearts 711, the King of Hearts 712 and the Two of Clubs 713. The player can then select which cards to hold from the first row 710 and these cards selected by the player are automatically duplicated in the other two rows 720 and 730. Again with reference to the example shown in FIG. 14, the player would most likely hold the Ace of Hearts 711 and the King of Hearts 712 as the cards to be duplicated into the other hands.

The first hand 710 then receives a replacement card for the card that is discarded. In this example as shown in FIG. 15, the first hand has a final hand of the Ace of Hearts 711, the King of Hearts 712 and the Six of Clubs 714. The second hand 720 has a final hand of the Ace of Hearts 711, the King of Hearts 712 and the Queen of Hearts 723. The third hand 730 has a final hand of the Ace of Hearts 711, the King of Hearts 712 and the Ace of Clubs 733.

The player now has three final three card hands and wins or loses on each hand separately based on a pay table which shows the winning hand combinations. If the player has a winning hand, the amount won by the player is based on the amount wagered by the player on that particular row and the poker hand ranking of the cards in that row. For example, again with reference to FIG. 15, in hand 710 the player has a three card Ace High which would probably be a losing hand based on a preferred pay table. In hand 720 the player has a three card Straight Flush and in hand 730 the player has a Pair of Aces which would all most likely be winning hands based on the preferred pay table.

Any suitable pay table may be used for this multiple hand version of a three card poker game. For illustration purposes, a representative pay table is shown in Table 1.

TABLE 1

Poker Hand Ranking	Per Coin Wagered
Straight Flush	25
Flush	6
Straight	5
Three-of-a-Kind	3
Any Pair	1

This version #E can also be applied to four card poker as shown in FIGS. 16-18. FIG. 16 shows an initial deal of a four card poker game which allows the player to play multiple hands. The player wagers on the number of hands the player wishes to play, for example the three rows shown in FIG. 16. The first hand 810 is dealt with all four cards face

up. Hand **810** is dealt with the Ace of Hearts **811**, the King of Hearts **812**, the Six of Clubs **813** and the Jack of Hearts. The player can then select which cards to hold from the first row **810** and these cards selected by the player are automatically duplicated in the other two rows **820** and **830**. Again with reference to the example shown in FIG. 17, the player would most likely hold the Ace of Hearts **811**, the King of Hearts **812** and the Jack of Hearts **814** as the cards to be duplicated into the other hands.

The first hand **810** then receives a replacement card for the card that is discarded. In this example as shown in FIG. 15, the first hand **810** has a final hand of the Ace of Hearts **811**, the King of Hearts **812**, the Six of Spades **815** and the Jack of Hearts **814**. The second hand **820** has a final hand of the Ace of Hearts **811**, the King of Hearts **812**, the Queen of Diamonds **823** and the Jack of Hearts **814**. The third hand **830** has a final hand of the Ace of Hearts **811**, the King of Hearts **812**, the Queen of Hearts **813** and the Jack of Hearts **814**.

The player now has three final four card hands and wins or loses on each hand separately based on a pay table which shows the winning hand combinations. If the player has a winning hand, the amount won by the player is based on the amount wagered by the player on that particular row and the poker hand ranking of the cards in that row. For example, again with reference to FIG. 18, in hand **810** the player has a four card Ace High which would probably be a losing hand based on the pay table. In hand **820** the player has a four card Straight and in hand **830** the player has a four card Straight Flush which would all most likely be winning hands based on the pay table.

Any suitable pay table may be used for this multiple hand version of a four card poker game. For illustration purposes, a representative pay table is shown in Table 2.

TABLE 2

Poker Hand Ranking	Per Coin Wagered
Straight Flush	100
Four-of-a-Kind	50
Flush	6
Straight	5
Three-of-a-Kind	3
Two Pair	2
Any Pair	1

This Version #E may also be applied to methods of play that use only two rows or that use four or more rows.

In addition to three, four or five card rows, the method of the present invention can also be applied to six, seven or more card rows. Winning hand combinations can be based on six card poker hand, seven card poker hands or even more card poker hands. Alternatively, the winning hand combinations can be based on the best five card poker hand out of the six, seven or even more cards in the row.

Alternatively, the method of play of any of the embodiments of the present invention can also use only one standard fifty-two card deck. In this alternative, each of the player's hands will receive different replacement cards from the single deck for those cards that are discarded. For example with reference to FIG. 3, if a player holds less than five cards from the top row **410**, each hand will receive different replacement cards so that player has the possibility of achieving various winning combinations.

In either the multiple deck embodiment or the single deck embodiment, one or more cards may alternatively be designated as wild cards or one or more Jokers may be added

to the deck or decks and designated as wild cards. This allows the methods of the present invention to be applied to any of the various wild card video poker games that are known in the art, such as Deuces Wild or Joker's Wild.

Special bonus payouts can be added if the player achieves, either on the deal or after the draw, three hands of the same rank at the same time. These bonus payouts could be fixed amounts or progressive payouts. For example, the player could win a progressive payout for achieving three Full Houses at the same time. As another example when three decks are used, the player can receive a large fixed or progressive payout if the player achieves the same poker hand in each of the three rows—such as a Royal Flush in Spades in all three rows.

The various embodiments of the present invention have been described in connection with a video display screen similar to conventional video poker in which each hand of cards is shown horizontally across the display screen. It is also possible to display the cards in other suitable formats. For example, a video slot machine reel format can be used in which the cards appear to spin in a vertical plane on the video display screen. The player would initiate the simulated spinning of reels after the player has made his wager on the number of pay lines which the player wishes to play. Each pay line would be the equivalent of a separate hand of cards.

When the reels stop spinning, a first hand of cards would be displayed on the video screen display along a first pay line. The player would select which of the initial cards from this first hand that the player wishes to hold. The held cards would be duplicated into the other pay lines upon which the player has wagered.

After the cards have been duplicated into the other pay lines, the player would activate a "DRAW" button which would cause the vertical columns that still need cards to simulate a spinning mode. When these columns stop spinning, each pay line would then have a complete poker hand. Each pay line is then analyzed to determine the poker hand ranking of the pay line and winning and losing card combinations are then determined. The award to the player is based on any winning combination on a pay line and the amount wagered by the player as shown in a pay table. One advantage of using spinning reel representations of the cards in each hand is that the pay lines do not have to be horizontal rows. The pay lines may also be diagonal lines or even W-shaped or M-shaped pay lines such as are used in other conventional slot machines having video reels.

While the various methods of play of the present invention have been described in the context of electronic video gaming machines, each method of play can also be carried on a live gaming table using a live dealer with the players arranged around the gaming table, in the manner in which other live table games such as a Twenty-One or card room poker is conducted.

While the invention has been illustrated with respect to several specific embodiments thereof, these embodiments should be considered as illustrative rather than limiting. Various modifications and additions may be made and will be apparent to those skilled in the art. Accordingly, the invention should not be limited by the foregoing description, but rather should be defined only by the following claims.

What is claimed is:

1. A method of playing a card game comprising:
- a) dealing a first hand of at least five cards all face up;
- b) selecting one or more of the face up cards from the first hand as cards to be held;
- c) duplicating the cards selected to be held from the first hand into a second hand;

11

- d) duplicating the cards selected to be held from the first hand into a third hand;
- e) discarding from the first hand the face up cards that were not selected to be held and replacing each of those cards with a face up card;
- f) completing the second hand to have at least five cards by dealing additional face up cards;
- g) completing the third hand to have at least five cards by dealing additional face up cards;
- h) determining the poker hand ranking of the resulting cards of the first hand, the second hand and the third hand.

2. The method of claim 1 including the steps of: a) a player making a first wager on the first hand, a second wager on the second hand and a third wager on the third hand; b) paying the player a pre-established amount based on the amount of the first wager if the resulting cards of the first hand comprise a predetermined poker hand ranking; c) paying the player a pre-established amount based on the amount of the second wager if the resulting cards of the second hand comprise a predetermined poker hand ranking; and d) paying the player a pre-established amount based on the amount of the third wager if the resulting cards of the third hand comprise a predetermined poker hand ranking.

3. A method of playing a card game comprising: a) dealing a first hand of at least five cards all face up; b) selecting one or more of the face up cards from the first hand as cards to be held; c) duplicating the cards selected to be held from the first hand into at least a second hand; d) discarding from the first hand the face up cards that were not selected to be held and replacing each of those cards with a face up card; e) completing the second hand and any additional hands to have at least five cards by dealing additional face up cards to each of the second hand and any additional hands; f) determining the poker hand ranking of the resulting cards of the first hand, the second hand and any additional hands.

4. The method of claim 3 including the steps of: a) a player making a first wager on the first hand, a second wager on the second hand and additional wagers on any additional hands, if any; b) paying the player a pre-established amount based on the amount of the first wager if the resulting cards of the first hand comprise a predetermined poker hand ranking; c) paying the player a pre-established amount based on the amount of the second wager if the resulting cards of the second hand comprise a predetermined poker hand ranking; and d) paying the player a pre-established amount based on the amount of any additional wagers, if any, if the resulting cards of any of the additional hands comprise a predetermined poker hand ranking.

5. The method of claim 3 including the steps of: a) a player making a first wager on the first hand, a second wager on the second hand and additional wagers on any additional hands; b) dependent on the number of wagers the player has made, dealing additional sets of face up replacement cards to the player's held cards creating additional five-card poker hands; c) paying the player a pre-established amount based on the amount of each wager if the resulting cards of any of the hands comprise a predetermined poker hand ranking.

6. A method of playing a card game comprising: a) dealing a first hand of at least five cards all face up; b) selecting one or more of the face up cards from the first hand as cards to be held; c) discarding from the first hand the face up cards that were not selected to be held and replacing each of those cards with a face up card; d) duplicating the cards selected to be held from the first hand into at least a second hand; e) completing the second hand to have at least five

12

cards by dealing additional face up cards to the second hand; f) determining the poker hand ranking of the resulting cards of the first hand and the second hand.

7. The method of claim 6 including the steps of: a) a player making a first wager on the first hand and a second wager on the second hand; b) paying the player a pre-established amount based on the amount of the first wager if the resulting cards of the first hand comprise a predetermined poker hand ranking; and c) paying the player a pre-established amount based on the amount of the second wager if the resulting cards of the second hand comprise a predetermined poker hand ranking.

8. The method of claim 6 including the steps of: a) a player making a first wager on the first hand, a second wager on the second hand and additional wagers on any additional hands; b) dependent on the number of wagers the player has made, dealing additional sets of face up replacement cards to the player's held cards creating additional five-card poker hands; c) paying the player a pre-established amount based on the amount of each wager if the resulting cards of any of the hands comprise a predetermined poker hand ranking.

9. A method of playing a card game comprising: a) dealing at least a first row and a second row of at least five cards all face up, each row having the same five cards; b) selecting one or more of the face up cards from either the first row or the second row as cards to be held; c) the same cards selected to be held from one row being also held in all of the other rows; d) discarding from each row the cards that were not selected to be held and replacing each of those cards with a face up card; e) determining the poker hand ranking of the resulting cards of each row.

10. The method of claim 9 including the steps of: a) a player making a first wager on each row; b) paying the player a pre-established amount based on the amount of the wager on each row if the resulting cards of each row comprise a predetermined poker hand ranking.

11. A method of playing a card game comprising: a) dealing a first row, a second row, a third row, a fourth row and a fifth row of at least five cards, with at least the cards in the first row being dealt all face up; b) selecting one or more of the face up cards from the first row as cards to be held; c) duplicating the cards selected to be held from the first row in all of the other rows; d) discarding from each row the cards that were not selected to be held and replacing each of those cards with a face up card; e) determining the poker hand ranking of the resulting cards of each row.

12. The method of claim 11 including the steps of: a) a player making a first wager on each row; b) paying the player a pre-established amount based on the amount of the wager on each row if the resulting cards of each row comprise a predetermined poker hand ranking.

13. A method of playing a card game comprising: a) dealing a first row, a second row, a third row, a fourth row, a fifth row, a sixth row, a seventh row, an eighth row, a ninth row and a tenth row of at least five cards, with at least the cards in the first row being dealt all face up; b) selecting one or more of the face up cards from the first row as cards to be held; c) duplicating the cards selected to be held from the first row in all of the other rows; d) discarding from each row the cards that were not selected to be held and replacing each of those cards with a face up card; and e) determining the poker hand ranking of the resulting cards of each row.

14. The method of claim 13 including the steps of: a) a player making a first wager on each row; b) paying the player a pre-established amount based on the amount of the wager on each row if the resulting cards of each row comprise a predetermined poker hand ranking.

13

15. A method of playing a card game comprising: a) dealing a first row, a second row, a third row, a fourth row, a fifth row, a sixth row, a seventh row, an eighth row, a ninth row and a tenth row of at least five cards, with each row having the same cards and the cards in each row being dealt all face up; b) selecting one or more of the face up cards from the first row as cards to be held; c) the same cards selected to be held from the first row being also held in all of the other rows; d) discarding from each row the cards that were not selected to be held and replacing each of those cards with a face up card; e) determining the poker hand ranking of the resulting cards of each row.

16. The method of claim 15 including the steps of: a) a player making a first wager on each row; b) paying the player a pre-established amount based on the amount of the wager on each row if the resulting cards of each row comprise a predetermined poker hand ranking.

17. A method of playing a card game comprising: a) dealing from a single deck of cards at least a first row and a second row of at least five cards all face up, each row having different cards and each card in the first row being vertically aligned in a column with adjacent cards in the other rows; b) selecting one or more of the face up cards as cards to be held with only one card in each vertical column being eligible for selection as a held card; c) each card selected to be held from one row being also held in all of the other rows; d) discarding from each row the cards that were not selected to be held and replacing each of those cards with a face up card; e) determining the poker hand ranking of the resulting cards of each row.

18. The method of claim 17 including the steps of: a) a player making a first wager on each row; b) paying the player a pre-established amount based on the amount of the wager on each row if the resulting cards of each row comprise a predetermined poker hand ranking.

19. A method of playing a card game comprising: a) dealing from a single deck of cards at least a first row and a second row of at least five cards all face up, each row having different cards; b) selecting one of the rows of cards as the row to be held; c) each card from the row selected to be held being duplicated into all of the other rows; d) selecting one or more of the face up cards from any one of the rows as cards to be held; e) the cards selected to be held in the one row being also held in the other rows; f) discarding from each row the cards that were not selected to be held and replacing each of those cards with a face up card; g) determining the poker hand ranking of the resulting cards of each row.

20. The method of claim 19 including the steps of: a) a player making a first wager on each row; b) paying the player a pre-established amount based on the amount of the wager on each row if the resulting cards of each row comprise a predetermined poker hand ranking.

21. A method of playing a card game comprising: a) dealing a first hand of at least five cards all face up; b) selecting one or more of the face up cards from the first hand as cards to be held; c) discarding from the first hand the cards that were not selected to be held and replacing each of those cards with a face up card; d) determining the poker hand ranking of the resulting cards of the first hand; e) re-dealing into a second hand the cards selected to be held from the first hand; f) completing the second hand to have at least five cards by dealing additional face up cards; and g) determining the poker hand ranking of the resulting cards of the second hand.

22. The method of claim 21 including the steps of: a) a player making a first wager on the first hand and a second

14

wager on the second hand; b) paying the player a pre-established amount based on the amount of the first wager if the resulting cards of the first hand comprise a predetermined poker hand ranking; and c) paying the player a pre-established amount based on the amount of the second wager if the resulting cards of the second hand comprise a predetermined poker hand ranking.

23. A method of playing a card game comprising: a) dealing a first hand of at least five cards all face up; b) 10 selecting one or more of the face up cards from the first hand as cards to be held; c) discarding from the first hand the cards that were not selected to be held and replacing each of those cards with a face up card; d) determining the poker hand ranking of the resulting cards of the first hand; e) re-dealing 15 into a second hand the cards selected to be held from the first hand; f) completing the second hand to have at least five cards by dealing additional face up cards; g) determining the poker hand ranking of the resulting cards of the second hand, h) redealing into a third hand the cards selected to be held 20 from the first hand; i) completing the third hand to have at least five cards by dealing additional face up cards; and j) determining the poker hand ranking of the resulting cards of the third hand.

24. The method of claim 23 including the steps of: a) a 25 player making a first wager on the first hand, a second wager on the second hand and a third wager on the third hand; b) paying the player a pre-established amount based on the amount of the first wager if the resulting cards of the first hand comprise a predetermined poker hand ranking; c) 30 paying the player a pre-established amount based on the amount of the second wager if the resulting cards of the second hand comprise a predetermined poker hand ranking; and d) paying the player a pre-established amount based on the amount of the third wager if the resulting cards of the third hand comprise a predetermined poker hand ranking.

25. A method of playing a card game comprising: a) a player making at least a first wager for a first hand and, optionally, additional wagers to be applied to a second and subsequent hands; b) dealing the first hand of at least five 40 cards all face up; c) selecting one or more of the face up cards from the first hand as cards to be held; d) discarding from the first hand the cards that were not selected to be held and replacing those each of those cards with a face up card; e) determining the poker hand ranking of the resulting cards of the first hand; f) paying the player a pre-established amount based on the amount of the first wager if the resulting cards of the first hand comprise a predetermined poker hand ranking; g) re-dealing seriatim into the second hand and any subsequent hands the cards selected to be held from the first hand; h) completing seriatim the second hand and any subsequent hands to have at least five cards by dealing additional face up cards; i) determining seriatim the poker hand ranking of the resulting cards of the second hand and any subsequent hands; and j) paying seriatim the player a pre-established amount based on the amount of the second wager and any subsequent wagers if the resulting cards of the second hand and any subsequent hands comprise a predetermined poker hand ranking.

26. A method of playing a card game comprising: a) 60 dealing a first hand of four cards all face up and a fifth card face down; b) selecting one or more of the face up cards from the first hand as cards to be held; c) duplicating the cards selected to be held from the first hand into a second hand; d) duplicating the cards selected to be held from the first hand into a third hand; e) discarding from the first hand the face up cards that were not selected to be held and replacing each of those cards with a face up card and

15

completing the first hand by displaying the fifth card face up; f) completing the second hand to have at least five cards by dealing additional face up cards; g) completing the third hand to have at least five cards by dealing additional face up cards; h) determining the poker hand ranking of the resulting cards of the first hand, the second hand and the third hand.

27. The method of claim 26 including the steps of: a) a player making a first wager on the first hand, a second wager on the second hand and a third wager on the third hand; b) paying the player a pre-established amount based on the amount of the first wager if the resulting cards of the first hand comprise a predetermined poker hand ranking; c) paying the player a pre-established amount based on the amount of the second wager if the resulting cards of the second hand comprise a predetermined poker hand ranking; and d) paying the player a pre-established amount based on the amount of the third wager if the resulting cards of the third hand comprise a predetermined poker hand ranking.

28. A method of playing a card game comprising: a) dealing a first hand of four cards all face up and a fifth card face down; b) selecting one or more of the face up cards from the first hand as cards to be held; c) duplicating the cards selected to be held from the first hand into at least a second hand and, optionally, any additional hands; d) discarding from the first hand the face up cards that were not selected to be held and replacing each of those cards with a face up card and completing the first hand by displaying a fifth card face up; e) completing the second hand and any additional hands to have at least five cards by dealing additional face up cards to each of the second hand and any additional hands; f) determining the poker hand ranking of the resulting cards of the first hand, the second hand and any additional hands.

29. The method of claim 28 including the steps of: a) a player making a first wager on the first hand, a second wager on the second hand and additional wagers on any additional hands, if any; b) paying the player a pre-established amount based on the amount of the first wager if the resulting cards of the first hand comprise a predetermined poker hand ranking; c) paying the player a pre-established amount based on the amount of the second wager if the resulting cards of the second hand comprise a predetermined poker hand ranking; and d) paying the player a pre-established amount based on the amount of any additional wagers, if any, if the resulting cards of any of the additional hands comprise a predetermined poker hand ranking.

30. A method of playing a card game comprising: a) dealing a first hand of five cards with some of the cards face up and the remaining cards face down; b) selecting one or more of the face up cards from the first hand as cards to be held; c) duplicating the cards selected to be held from the first hand into a second hand; d) duplicating the cards selected to be held from the first hand into a third hand; e) discarding from the first hand the face up cards that were not selected to be held and replacing each of those cards with a face up card and completing the first hand by displaying the face down cards face up; f) completing the second hand to have at least five cards by dealing additional face up cards; g) completing the third hand to have at least five cards by dealing additional face up cards; h) determining the poker hand ranking of the resulting cards of the first hand, the second hand and the third hand.

31. The method of claim 30 including the steps of: a) a player making a first wager on the first hand, a second wager on the second hand and a third wager on the third hand; b) paying the player a pre-established amount based on the amount of the first wager if the resulting cards of the first

16

hand comprise a predetermined poker hand ranking; c) paying the player a pre-established amount based on the amount of the second wager if the resulting cards of the second hand comprise a predetermined poker hand ranking; and d) paying the player a pre-established amount based on the amount of the third wager if the resulting cards of the third hand comprise a predetermined poker hand ranking.

32. A method of playing a card game comprising: a) dealing a first hand of five cards with some of the cards face up and remaining cards face down; b) selecting one or more of the face up cards from the first hand as cards to be held; c) duplicating the cards selected to be held from the first hand into at least a second hand and, optionally, any additional hands; d) discarding from the first hand the face up cards that were not selected to be held and replacing each of those cards with a face up card and completing the first hand by displaying the remaining face down cards face up; e) completing the second hand and any additional hands to have at least five cards by dealing additional face up cards to each of the second hand and any additional hands; f) determining the poker hand ranking of the resulting cards of the first hand, the second hand and any additional hands.

33. The method of claim 32 including the steps of: a) a player making a first wager on the first hand, a second wager on the second hand and additional wagers on any additional hands, if any; b) paying the player a pre-established amount based on the amount of the first wager if the resulting cards of the first hand comprise a predetermined poker hand ranking; c) paying the player a pre-established amount based on the amount of the second wager if the resulting cards of the second hand comprise a predetermined poker hand ranking; and d) paying the player a pre-established amount based on the amount of any additional wagers, if any, if the resulting cards of any of the additional hands comprise a predetermined poker hand ranking.

34. A method of playing a card game comprising: a) dealing a first hand of three cards all face up; b) selecting one or more of the face up cards from the first hand as cards to be held; c) duplicating the cards selected to be held from the first hand into at least a second hand; d) discarding from the first hand the face up cards that were not selected to be held and replacing each of those cards with a face up card; e) completing the second hand and any additional hands to have three cards by dealing additional face up cards to each of the second hand and any additional hands; f) determining the poker hand ranking of the resulting cards of the first hand, the second hand and any additional hands.

35. The method of claim 34 including the steps of: a) a player making a first wager on the first hand, a second wager on the second hand and additional wagers on any additional hands, if any; b) paying the player a pre-established amount based on the amount of the first wager if the resulting cards of the first hand comprise a predetermined poker hand ranking; c) paying the player a pre-established amount based on the amount of the second wager if the resulting cards of the second hand comprise a predetermined poker hand ranking; and d) paying the player a pre-established amount based on the amount of any additional wagers, if any, if the resulting cards of any of the additional hands comprise a predetermined poker hand ranking.

36. The method of claim 35 wherein the pre-established amount is based on a pay table.

37. The method of claim 36 in which the pay table comprises:

Poker Hand Ranking	Per Coin Wagered
Straight Flush	25
Flush	6
Straight	5
Three-of-a-Kind	3
Any Pair	1.

38. A method of playing a card game comprising: a) dealing a first hand of four cards all face up; b) selecting one or more of the face up cards from the first hand as cards to be held; c) duplicating the cards selected to be held from the first hand into at least a second hand; d) discarding from the first hand the face up cards that were not selected to be held and replacing each of those cards with a face up card; e) completing the second hand and any additional hands to have four cards by dealing additional face up cards to each of the second hand and any additional hands; f) determining the poker hand ranking of the resulting cards of the first hand, the second hand and any additional hands.

39. The method of claim **38** including the steps of: a) a player making a first wager on the first hand, a second wager on the second hand and additional wagers on any additional hands, if any; b) paying the player a pre-established amount based on the amount of the first wager if the resulting cards of the first hand comprise a predetermined poker hand ranking; c) paying the player a pre-established amount based on the amount of the second wager if the resulting cards of the second hand comprise a predetermined poker hand ranking; and d) paying the player a pre-established amount based on the amount of any additional wagers, if any, if the resulting cards of any of the additional hands comprise a predetermined poker hand ranking.

40. The method of claim **39** wherein the pre-established amount is based on a pay table.

41. The method of claim **40** in which the pay table comprises:

Poker Hand Ranking	Per Coin Wagered
Straight Flush	100
Four-of-a-Kind	50
Flush	6
Straight	5
Three-of-a-Kind	3
Two Pair	2
Any Pair	1.

42. A method of playing a card game comprising: a) displaying a first hand of at least five cards all face up; b) selecting one or more of the face up cards from the first hand as cards to be held; c) discarding from the first hand the cards that were not selected to be held and replacing each of those cards with a face up card; d) determining the poker hand ranking of the resulting cards of the first hand e) re-displaying into a second hand the cards selected to be held from the first hand; f) completing the second hand to have at least five cards by displaying additional face up cards; and g) determining the poker hand ranking of the resulting cards of the second hand.

43. The method of claim **42** including the steps of: a) a player making a first wager on the first hand and a second wager on the second hand; b) paying the player a pre-established amount based on the amount of the first wager if the resulting cards of the first hand comprise a predeter-

mined poker hand ranking; and c) paying the player a pre-established amount based on the amount of the second wager if the resulting cards of the second hand comprise a predetermined poker hand ranking.

44. A method of playing a card game comprising: a) displaying a first hand of at least five cards all face up; b) selecting one or more of the face up cards from the first hand as cards to be held; c) discarding from the first hand the cards that were not selected to be held and replacing each of those cards with a face up card; d) determining the poker hand ranking of the resulting cards of the first hand e) re-displaying into a second hand the cards selected to be held from the first hand; f) completing the second hand to have at least five cards by displaying additional face up cards; g) determining the poker hand ranking of the resulting cards of the second hand; h) re-displaying into a third hand the cards selected to be held from the first hand; i) completing the third hand to have at least five cards by displaying additional face up cards; and j) determining the poker hand ranking of the resulting cards of the third hand.

45. The method of claim **44** including the steps of: a) a player making a first wager on the first hand, a second wager on the second hand and a third wager on the third hand; b) paying the player a pre-established amount based on the amount of the first wager if the resulting cards of the first hand comprise a predetermined poker hand ranking; c) paying the player a pre-established amount based on the amount of the second wager if the resulting cards of the second hand comprise a predetermined poker hand ranking; and d) paying the player a pre-established amount based on the amount of the third wager if the resulting cards of the third hand comprise a predetermined poker hand ranking.

46. A method of playing a card game comprising: a) a player making at least a first wager for a first hand and, optionally, additional wagers to be applied to a second and subsequent hands; b) displaying the first hand of at least five cards all face up; c) selecting one or more of the face up cards from the first hand as cards to be held; d) discarding from the first hand the cards that were not selected to be held and replacing each of those cards with a face up card; e) determining the poker hand ranking of the resulting cards of the first hand; f) paying the player a pre-established amount based on the amount of the first wager if the resulting cards of the first hand comprise a predetermined poker hand ranking; g) re-displaying seriatim into the second hand and any subsequent hands the cards selected to be held from the first hand; h) completing seriatim the second hand and any subsequent hands to have at least five cards by displaying additional face up cards; i) determining seriatim the poker hand ranking of the resulting cards of the second hand and any subsequent hands; and j) paying seriatim the player a pre-established amount based on the amount of the second wager and any subsequent wagers if the resulting cards of the second hand and any subsequent hands comprise a predetermined poker hand ranking.

47. A method of playing a card game comprising: a) displaying a first hand of four cards all face up and a fifth card face down; b) selecting one or more of the face up cards from the first hand as cards to be held; c) duplicating the cards selected to be held from the first hand into a second hand; d) duplicating the cards selected to be held from the first hand into a third hand; e) discarding from the first hand the face up cards that were not selected to be held and replacing each of those cards with a face up card and completing the first hand by displaying the fifth card face up; f) completing the second hand to have at least five cards by displaying additional face up cards; g) completing the third

19

hand to have at least five cards by displaying additional face up cards; h) determining the poker hand ranking of the resulting cards of the first hand, the second hand and the third hand.

48. The method of claim **47** including the steps of: a) a player making a first wager on the first hand, a second wager on the second hand and a third wager on the third hand; b) paying the player a pre-established amount based on the amount of the first wager if the resulting cards of the first hand comprise a predetermined poker hand ranking; c) paying the player a pre-established amount based on the amount of the second wager if the resulting cards of the second hand comprise a predetermined poker hand ranking; and d) paying the player a pre-established amount based on the amount of the third wager if the resulting cards of the third hand comprise a predetermined poker hand ranking.

49. A method of playing a card game comprising: a) displaying a first hand of four cards all face up and a fifth card face down; b) selecting one or more of the face up cards from the first hand as cards to be held; c) duplicating the cards selected to be held from the first hand into at least a second hand and, optionally, any additional hands; d) discarding from the first hand the face up cards that were not selected to be held and replacing each of those cards with a face up card and completing the first hand by displaying a fifth card face up; e) completing the second hand and any additional hands to have at least five cards by displaying additional face up cards to each of the second hand and any additional hands; f) determining the poker hand ranking of the resulting cards of the first hand, the second hand and any additional hands.

50. The method of claim **49** including the steps of: a) a player making a first wager on the first hand, a second wager on the second hand and additional wagers on any additional hands, if any; b) paying the player a pre-established amount based on the amount of the first wager if the resulting cards of the first hand comprise a predetermined poker hand ranking; c) paying the player a pre-established amount based on the amount of the second wager if the resulting cards of the second hand comprise a predetermined poker hand ranking; and d) paying the player a pre-established amount based on the amount of any additional wagers, if any, if the resulting cards of any of the additional hands comprise a predetermined poker hand ranking.

51. A method of playing a card game comprising: a) displaying a first hand of five cards with some of the cards face up and the remaining cards face down; b) selecting one or more of the face up cards from the first hand as cards to be held; c) duplicating the cards selected to be held from the first hand into a second hand; d) duplicating the cards selected to be held from the first hand into a third hand; e) discarding from the first hand the face up cards that were not selected to be held and replacing each of those cards with a face up card and completing the first hand by displaying the face down cards face up; f) completing the second hand to have at least five cards by displaying additional face up cards; g) completing the third hand to have at least five cards by displaying additional face up cards; h) determining the poker hand ranking of the resulting cards of the first hand, the second hand and the third hand.

52. The method of claim **51** including the steps of: a) a player making a first wager on the first hand, a second wager on the second hand and a third wager on the third hand; b) paying the player a pre-established amount based on the amount of the first wager if the resulting cards of the first hand comprise a predetermined poker hand ranking; c) paying the player a pre-established amount based on the

20

amount of the second wager if the resulting cards of the second hand comprise a predetermined poker hand ranking; and d) paying the player a pre-established amount based on the amount of the third wager if the resulting cards of the third hand comprise a predetermined poker hand ranking.

53. A method of playing a card game comprising: a) displaying a first hand of five cards with some of the cards face up and remaining cards face down; b) selecting one or more of the face up cards from the first hand as cards to be held; c) duplicating the cards selected to be held from the first hand into at least a second hand and, optionally, any additional hands; d) discarding from the first hand the face up cards that were not selected to be held and replacing each of those cards with a face up card and completing the first hand by displaying the remaining face down cards face up; e) completing the second hand and any additional hands to have at least five cards by displaying additional face up cards to each of the second hand and any additional hands; f) determining the poker hand ranking of the resulting cards of the first hand, the second hand and any additional hands.

54. The method of claim **53** including the steps of: a) a player making a first wager on the first hand, a second wager on the second hand and additional wagers on any additional hands, if any; b) paying the player a pre-established amount based on the amount of the first wager if the resulting cards of the first hand comprise a predetermined poker hand ranking; c) paying the player a pre-established amount based on the amount of the second wager if the resulting cards of the second hand comprise a predetermined poker hand ranking; and d) paying the player a pre-established amount based on the amount of any additional wagers, if any, if the resulting cards of any of the additional hands comprise a predetermined poker hand ranking.

55. A method of playing a card game comprising: a) displaying a first hand of three cards all face up; b) selecting one or more of the face up cards from the first hand as cards to be held; c) duplicating the cards selected to be held from the first hand into at least a second hand; d) discarding from the first hand the face up cards that were not selected to be held and replacing each of those cards with a face up card; e) completing the second hand and any additional hands to have three cards by displaying additional face up cards to each of the second hand and any additional hands; f) determining the poker hand ranking of the resulting cards of the first hand, the second hand and any additional hands.

56. The method of claim **55** including the steps of: a) a player making a first wager on the first hand, a second wager on the second hand and additional wagers on any additional hands, if any; b) paying the player a pre-established amount based on the amount of the first wager if the resulting cards of the first hand comprise a predetermined poker hand ranking; c) paying the player a pre-established amount based on the amount of the second wager if the resulting cards of the second hand comprise a predetermined poker hand ranking; and d) paying the player a pre-established amount based on the amount of any additional wagers, if any, if the resulting cards of any of the additional hands comprise a predetermined poker hand ranking.

57. The method of claim **56** wherein the pre-established amount is based on a pay table.

58. The method of claim **57** in which the pay table comprises:

Poker Hand Ranking	Per Coin Wagered
Straight Flush	25
Flush	6
Straight	5
Three-of-a-Kind	3
Any Pair	1.

59. A method of playing a card game comprising: a) displaying a first hand of four cards all face up; b) selecting one or more of the face up cards from the first hand as cards to be held; c) duplicating the cards selected to be held from the first hand into at least a second hand; d) discarding from the first hand the face up cards that were not selected to be held and replacing each of those cards with a face up card; e) completing the second hand and any additional hands to have four cards by displaying additional face up cards to each of the second hand and any additional hands; f) determining the poker hand ranking of the resulting cards of the first hand, the second hand and any additional hands.

60. The method of claim 59 including the steps of: a) a player making a first wager on the first hand, a second wager on the second hand and additional wagers on any additional hands, if any; b) paying the player a pre-established amount based on the amount of the first wager if the resulting cards of the first hand comprise a predetermined poker hand ranking; c) paying the player a pre-established amount based on the amount of the second wager if the resulting cards of the second hand comprise a predetermined poker hand ranking; and d) paying the player a pre-established amount based on the amount of any additional wagers, if any, if the resulting cards of any of the additional hands comprise a predetermined poker hand ranking.

61. The method of claim 60 wherein the pre-established amount is based on a pay table.

62. The method of claim 61 in which the pay table comprises:

Poker Hand Ranking	Per Coin Wagered
Straight Flush	100
Four-of-a-Kind	50
Flush	6
Straight	5
Three-of-a-Kind	3
Two Pair	2
Any Pair	1.

63. A method of playing a card game in which a plurality of pay lines are used and a wager is made to activate each pay line comprising: a) displaying a first row of five cards; b) selecting one or more of the cards from the first row of cards as cards to be held; c) re-using the cards selected to be held from the first row of cards in a second row of cards; d) re-using the cards selected to be held from the first row of cards in a third row of cards; e) discarding from the first row of cards the unselected cards and replacing each of the unselected cards with a replacement card; f) providing additional cards to the second row of cards so that the second row of cards has five cards; g) providing additional cards to the third row of cards so that the third row of cards has five cards; h) each pay line comprising a grouping of five cards from one or more of the first row of cards, the second row of cards and the third row of cards; and i) determining the poker hand ranking of the resulting cards of each pay line.

64. The method of claim 63 wherein one of the pay lines comprises the five cards in the first row of cards.

65. The method of claim 63 wherein one of the pay lines comprises the five cards in the second row of cards.

66. The method of claim 63 wherein one of the pay lines comprises the five cards in the third row of cards.

67. The method of claim 63 wherein one of the pay lines comprises two cards from the first row of cards, two cards from the second row of cards and one card from the third row of cards.

10 68. The method of claim 63 wherein one of the pay lines comprises two cards from the first row of cards, one card from the second row of cards and two cards from the third row of cards.

15 69. The method of claim 63 wherein one of the pay lines comprises one card from the first row of cards, two cards from the second row of cards and two cards from the third row of cards.

20 70. The method of claim 63 wherein the number of pay lines selected exceeds the number of rows of the cards.

71. The method of claim 63 including paying the player an award based on the poker hand ranking of the pay line and the amount of the player's wager on that pay line according to a pay table.

25 72. The method of claim 63 including the step of a player placing a single wager for each pay line to be played.

73. The method of claim 63 including the step of a player placing a wager to play multiple pay lines.

30 74. The method of claim 63 wherein the replacement cards and additional cards provided in accordance with steps e), f) and g) are provided from a single deck of cards.

35 75. The method of claim 63 wherein the replacement cards in accordance with step e) are provided from a first deck of cards, the additional cards provided in accordance with step f) are provided from a second deck of cards, and the additional cards provided in accordance with step g) are provided from a third deck of cards.

76. A method of playing a card game in which a plurality of pay lines are used and a wager is made to activate each pay line comprising: a) providing a fifteen-card display

40 having a first row, a second row and a third row with each row having five card locations; b) displaying cards at each of the five card locations in the first row; c) selecting one or more of the cards from the first row as cards to be held; d) re-using the cards selected to be held from the first row in

45 card locations in the second row; e) re-using the cards selected to be held from the first row in card locations in the third row; f) discarding from the first row the unselected cards and replacing each of the unselected cards with a replacement card; g) providing additional cards to the sec-

50 ond row so that the second row has five cards; h) providing additional cards to the third row so that the third row has five cards; i) selecting one or more hands comprising five cards from the fifteen card locations, each pay line comprising one of the hands of five cards selected from the fifteen card

55 locations; and j) determining the poker hand ranking of the resulting cards of each pay line.

77. The method of claim 76 wherein one of the pay lines comprises the hand of five cards comprising the first row of cards.

60 78. The method of claim 76 wherein one of the pay lines comprises the hand of five cards comprising the second row of cards.

79. The method of claim 76 wherein one of the pay lines comprises the hand of five cards comprising the third row of cards.

65 80. The method of claim 76 wherein one of the pay lines comprises a hand comprising two cards from the first row of

cards, two cards from the second row of cards and one card from the third row of cards.

81. The method of claim 76 wherein one of the pay lines comprises a hand comprising two cards from the first row of cards, one card from the second row of cards and two cards from the third row of cards.

82. The method of claim 76 wherein one of the pay lines comprises a hand comprising one card from the first row of cards, two cards from the second row of cards and two cards from the third row of cards.

83. The method of claim 76 wherein the number of pay lines selected exceeds the number of rows of the cards.

84. The method of claim 76 including paying the player an award based on the poker hand ranking of the hand of each pay line and the amount of the player's wager on that pay line according to a pay table.

85. The method of claim 76 including the step of a player placing a single wager for each pay line to be played.

86. The method of claim 76 including the step of a player placing a wager to play multiple pay lines.

87. The method of claim 76 wherein the replacement cards and additional cards provided in accordance with steps f), g) and h) are provided from a single deck of cards.

88. The method of claim 76 wherein the replacement cards in accordance with step f) are provided from a first deck of cards, the additional cards provided in accordance with step g) are provided from a second deck of cards, and the additional cards provided in accordance with step h) are provided from a third deck of cards.

89. A method of playing a game in which a plurality of pay lines are used and a wager is made to activate each pay line comprising: a) displaying a first row of symbols; b) selecting one or more of the symbols from the first row of symbols as symbols to be held; c) re-using the symbols selected to be held from the first row of symbols in a second row of symbols; d) re-using the symbols selected to be held from the first row of symbols in a third row of symbols; e) discarding from the first row of symbols the unselected symbols and replacing each of the unselected symbols with a replacement symbol; f) providing additional symbols to the second row of symbols so that the second row of symbols has the same number of symbols as the first row; g) providing additional symbols to the third row of symbols so that the third row of symbols has the same number of symbols as the first row; h) each pay line comprising a grouping of symbols from one or more of the first row of symbols, the second row of symbols and the third rows of symbols; and i) determining the symbol ranking of the resulting symbols of each pay line.

90. The method of claim 89 wherein one of the pay lines comprises the symbols of the first row of symbols.

91. The method of claim 89 wherein one of the pay lines comprises the symbols of the second row of symbols.

92. The method of claim 89 wherein one of the pay lines comprises the symbols of the third row of symbols.

93. The method of claim 89 wherein each of the first row, second row and third row has five symbols.

94. The method of claim 89 wherein one of the pay lines comprises two symbols from the first row of symbols, two symbols from the second row of symbols and one symbol from the third row of symbols.

95. The method of claim 89 wherein one of the pay lines comprises two symbols from the first row of symbols, one symbol from the second row of symbols and two symbols from the third row of symbols.

96. The method of claim 89 wherein one of the pay lines comprises one symbol from the first row of symbols, two

symbols from the second row of symbols and two symbols from the third row of symbols.

97. The method of claim 89 wherein the number of pay lines activated exceeds the number of rows of the symbols.

98. The method of claim 89 including paying the player an award based on the ranking of the group of symbols of the pay line and the amount of the player's wager on that pay line according to a pay table.

99. The method of claim 89 including the step of a player placing a single wager for each pay line to be played.

100. The method of claim 89 including the step of a player placing a wager to play multiple pay lines.

101. A method of playing a card game comprising: a) dealing a first hand of at least four cards all face up; b) selecting one or more of the face up cards from the first hand as cards to be held; c) duplicating the cards selected to be held from the first hand into a second hand; d) duplicating the cards selected to be held from the first hand into a third hand; e) discarding from the first hand at least one card, the card being a card not selected to be held, and replacing any discarded card with a face up card and completing the first hand by displaying a fifth card face up; f) completing the second hand to have at least five cards by dealing additional face up cards; g) completing the third hand to have at least five cards by dealing additional face up cards; and h) determining the poker hand ranking of the resulting cards of the first hand, the second hand and the third hand.

102. The method of claim 101 including the steps of: a) a player making a first wager on the first hand, a second wager on the second hand and a third wager on the third hand; and b) paying the player a pre-established amount based on the amount of the first wager if the resulting cards of the first hand comprise a predetermined poker hand ranking; c) paying the player a pre-established amount based on the amount of the second wager if the resulting cards of the second hand comprise a predetermined poker hand ranking; and d) paying the player a pre-established amount based on the amount of the third wager if the resulting cards of the third hand comprise a predetermined poker hand ranking.

103. A method of playing a card game by only a single player comprising: a) dealing a first hand of at least four cards all face up; b) selecting one or more of the face up cards from the first hand as cards to be held; c) re-using cards from the first hand in a second hand; d) re-using cards from the first hand in a third hand; e) discarding from the first hand at least one card, the card being a card not selected to be held, and replacing any discarded card with a face up card and completing the first hand by displaying a fifth card face up; f) completing the second hand to have at least five cards by dealing additional face up cards; g) completing the third hand to have at least five cards by dealing additional face up cards; and h) determining the poker hand ranking of the resulting cards of the first hand, the second hand and the third hand.

104. The method of claim 103 including the steps of: a) a player making a first wager on the first hand, a second wager on the second hand and a third wager on the third hand; and b) paying the player a pre-established amount based on the amount of the first wager if the resulting cards of the first hand comprise a predetermined poker hand ranking; c) paying the player a pre-established amount based on the amount of the second wager if the resulting cards of the second hand comprise a predetermined poker hand ranking; and d) paying the player a pre-established amount based on the amount of the third wager if the resulting cards of the third hand comprise a predetermined poker hand ranking.

105. A method of playing a card game by only a single player comprising: a) displaying at least a first hand and a second hand of at least five cards all face up, each hand having the same five cards; b) selecting one or more of the face up cards from the first hand and the second hand as cards to be held; c) discarding from each hand the cards that were not selected to be held and replacing each of those cards with a face up card; and d) determining the poker hand ranking of the resulting cards of each hand.

106. The method of claim **105** including the steps of: a) a player making a wager on each hand; and b) paying the player a pre-established amount based on the amount of the wager on each hand if the resulting cards of each hand comprise a predetermined poker hand ranking.

107. A method of playing a card game comprising: a) a player making a wager on each hand; b) the player receiving at least a first hand and a second hand of at least five cards all face up, each hand having the same five cards; c) selecting one or more of the face up cards from the first hand and the second hand and any additional hands as cards to be held; d) discarding from each hand the cards that were not selected to be held and replacing each of those cards with a face up card; e) determining the poker hand ranking of the resulting cards of each hand; and f) paying the player a pre-established amount based on the amount of the wager on each hand if the resulting cards of each hand comprise a predetermined poker hand ranking.

108. A method of playing a card game comprising: a) displaying at least five cards all face up in at least two hands, each hand having the same five cards; b) allowing the player the option of playing each hand by selecting one or more of the face up cards from each hand as cards to be held; c) discarding from each hand the cards that were not selected to be held and replacing each of those cards with a face up card; and d) determining the poker hand ranking of the resulting cards of each hand.

109. The method of claim **108** including the steps of: a) a player making a wager on each hand; and b) paying the player a pre-established amount based on the amount of the wager on each hand if the resulting cards of each hand comprise a predetermined poker hand ranking.

110. A method of playing a card game comprising: a) a player making a wager; b) displaying at least five cards all face up in at least two hand, each hand having the same five cards; c) allowing the player the option of playing each hand by selecting one or more of the face up cards from each hand as cards to be held; d) discarding from each hand the cards that were not selected to be held and replacing each of those cards with a face up card; and e) determining the poker hand ranking of the resulting cards of each hand; and f) paying the player a pre-established amount based on the amount of the wager on each hand if the resulting cards of each hand comprise a predetermined poker hand ranking.
